[57] CLAIM

The ornamental design for a vehicle seat bolster, as shown and described.

DESCRIPTION

FIG. 1 is a perspective view of a vehicle seat bolster showing the ornamental design according to my invention;

FIG. 2 is a reversed perspective view of a vehicle seat bolster showing the ornamental design according to my invention;
FIG. 3 is a front view of a vehicle seat bolster showing the ornamental design according to my invention;

FIG. 4 is a left-side view of a vehicle seat bolster showing the ornamental design according to my invention, the opposite side being a mirror image thereof;

FIG. 5 is a top view of a vehicle seat bolster showing the ornamental design according to my invention; and,

FIG. 6 is a bottom view of a vehicle seat bolster showing the ornamental design according to my invention.
The broken lines showing a seat in all views are for illustrative purposes only and form no part of the claimed design.

FIGS. 2 through 6 have been shown on a reduced scale.
